ADJUSTABLE LIGHTING FIXTURE AND WALL RECESS COMBINATION

Brian Copping, New York, N.Y., assignor to Swivelier Company, Inc., Nanuet, N.Y., a corporation of New York

Filed July 15, 1959, Ser. No. 56,793

Term of patent 14 years

(Cl. D48—4)

Figure 1 is a perspective view of an adjustable lighting fixture and wall recess combination, showing my new design.

Figure 2 is a perspective view thereof with the light member shown in an alternate adjusted position.

Figure 3 is a front elevational view thereof as shown in Figure 1.

Figure 4 is a side elevational view thereof.

Figure 5 is a top plan view thereof.

Figure 6 is a bottom view thereof with the light member in an outwardly projecting position.

I claim:

The ornamental design for an adjustable lighting fixture and wall recess combination, as shown.
